DESIGN.

—o—

J. L. FOLSOM.

CARPET.

No. 18,124.

Patented Mar. 6, 1888.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 18,124, dated March 6, 1888.

Application filed January 26, 1888. Serial No. 262,044. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists, principally, of several large groups of conventionalized flower and

leaf forms disposed over the surface of the carpet, as shown. The central group is ornamented with small clusters of star-shaped 20 flower forms. At one side of the photograph is shown a large single flower form separate from the groups. In the spaces between the groups are clusters of small star-shaped flowers and small leaves partially connected and 25 intersected with a fine stem-work.

What I claim as new, and desire to secure by Letters Patent, is—

The design for carpets, consisting of the design substantially as shown.

JAS. L. FOLSOM.
